[57] CLAIM

The ornamental design for an electronic thermometer, as shown and described.

DESCRIPTION

FIG. 1 is a front perspective view of an electronic thermometer showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a left side elevational view thereof with the probe arm in a raised position.
